FOREIGN PATENT DOCUMENTS

WO 2013179318 A1 12/2013

Primary Examiner — Sheryl Lane

(74) Attorney, Agent, or Firm — Pearne & Gordon LLP

(57) **CLAIM**

The ornamental design for a head trimmer, as shown and described.

DESCRIPTION

FIG. 1 is a perspective view of a head trimmer, showing my new design;

FIG. 2 is a top view thereof;

FIG. 3 is a left side view thereof;

FIG. 4 is a front view thereof;

FIG. 5 is a back view thereof;

FIG. 6 is a right side view thereof; and,

FIG. 7 is a bottom view thereof.

The broken lines in the drawings represent unclaimed subject matter and form no part of the claimed design.
